GUSTAV BORGESON, OF SYRACUSE, NEW YORK.

SHEET-FEEDING MECHANISM.

Application filed March 12, 1928. Serial No. 260,852.

This invention relates to sheet feeding mechanism in which sheets are fed edgewise one after another from the top of a stack of sheets, as in serving sheets to a printing machine. The object is to provide a sheet feeding mechanism of this class which shall be of simple construction and reliable in operation and in which the sheets will be handled without disturbance of the stack and 10 without the rubbing of the sheets on each other, which in some instances of the application of the mechanism, as in serving lithographing or printing machines operating on the sheets in sequence, would injure the sheets by obliterating or marring what is already printed thereon.

In the drawing,

Fig. 1 is a side elevation of the improved mechanism;

20 Fig. 2 is a plan;

Fig. 3 is a rear elevation;

Figs. 4 and 5 are a rear elevation and a plan, partly in section, of one of the suction-controlling valves; and

25 Fig. 6 a side elevation of a certain clip or detent for the carriage.

Let 1 designate the intake rolls of a printing press a portion of whose frame is indicated at 2 and may have a table or equivalent 30 3 for the stack A of sheets to be fed one after another to the rolls 1. The support afforded by the frame and table may carry or include pairs of brackets 5, one pair at each side of the stack, and, secured in each such 35 pair, a shaft 6, such shafts affording a guideway for a carriage.

This carriage 7 may be a flat bar having end guides 7^a apertured to receive and slide on said guideway and also end trunnions 7^b 40 to which are connected the levers 8 by which through pitmen 9 the carriage is connected with crank pins 10^a on crank disks 10 of a rotating shaft 11 of the press, whereby the carriage is reciprocated on the guideway 45 when the press is operating; for a purpose to appear each lever has an upwardly open notch 8^a receiving the trunnion 7^b, being thus forked, so that the connection between the rectilineally moving carriage and the oscillating lever is a sliding one.

50 Suction elements are mounted on the carriage. Each of these includes, slidably vertically in a tubular upstanding guide 12 having its basal flange 12^a secured to the bar of 55 and thus forming in effect a part of the carriage, a stem 13^b and a cup 13^a on the lower

end of the stem; each suction element is normally held elevated clear of the stack A by a spiral spring 14 housed in the guide and interposed between shoulders 15 and 16 of the 60 carriage and stem, respectively, as shown by dotted lines in Fig. 1. Each stem has a port 13^c leading upwardly from its cup to a nipple 13^d, and it also has at the top an anti-friction roller 13^e. The carriage is equipped 65 with a suction controlling valve whose valve casing 18 has its valve chamber provided on the one hand with an exhaust port in a nipple 18^a by which, through a flexible tube 19, the valve chamber may be connected with 70 suitable exhaust means, and on the other hand with intake ports in nipples 18^b which may be connected with the nipples 13^d of the suction elements by flexible tubes 19^a; the valve casing also has a port 18^c leading to the 75 atmosphere. The valve proper 20, projecting from the casing, is normally held in the position for permitting flow through the casing from the suction appliances to the exhaust means by a spiral spring 21 interposed 80 between its head 20^a and the valve casing; when it is pressed inward it will close off the communication through the valve casing (see Fig. 5) and place the suction elements in communication with the atmosphere via 85 18^c.

When the carriage recedes (moves to the right) the suction devices are depressed into suction contact with the topmost sheet, and when it moves forward they must be permitted to rise to lift the sheet from the stack. 90 For this purpose there is a depresser (here in effect a lever structure) for the suction devices which is actuated by the levers 8 and comprises a rock-shaft 22 journaled in the 95 two rearward brackets 5, a pair of cams 23 thereon which overhang the suction devices when in the rearward portions of their movements, and a pair of crank arms 24 having rollers 24^a to assume the thrust of 100 the levers 8 as they swing back. When, following depression of the suction devices by the levers 8 acting through the depresser, the levers begin to return to advance the carriage and hence the topmost sheet adhering to the suction devices, the latter are caused by springs 14 to rise (incidentally resetting the depresser) and lift the sheet clear of the stack; the nip of the intake rolls is in a lower plane than that assumed by the 105 acting faces of the fully elevated suction cups, but the sheet as shown is gripped by 110

the suction devices near its rear edge, and so its weight bends it downward so that its forward edge is more or less opposite the nip of the rolls. Upon the sheet being caught by the intake rolls 1 the valves proper 20 encounter adjustable stops 25 on the brackets 5 and the suction is cut off and the cups being put in communication with the atmosphere at 18° the sheet is released by the suction elements.

When the suction elements are depressed against the topmost sheet they should not be undergoing movement in the rearward direction or the stack will be disturbed. Hence, about when the levers 8 begin to effect depression of the suction elements they cease to repress the carriage, which thereupon stops, this being effected by forming the forward portions of the forks of the levers (see Fig. 1) shorter than their rearward portions so that at the proper point the trunnions 7^b are cleared. The carriage may be brought to a positive stop by studs 7^c thereon engaging clips such as that shown in Fig. 6 comprising two jaws 26-27 of which jaw 26 is fixed to a portion of one of the rear brackets 5 by a screw 28 and the other jaw is pivoted on the screw and is pressed toward the fixed clip by a spring 29 interposed between jaw 26 and the head of a stem 30 penetrating both clips and having support at 31 on the fixed clip.

To prevent failure of feed due to possible failure of the suction-grip to hold during forward feeding of the sheet I provide pivoted detents 32. These may rise pivotally from but are stopped from fall below the position thereof shown in Fig. 1. They are pivoted in rebent arms 32^a secured to the carriage by screws 33 penetrating slots 34 in the arms extending lengthwise of the path of movement of the carriage, so that the detents may be adjusted correspondingly. When a sheet is lifted its rear edge trips the detents upward and passing the same is positioned to be held elevated by the detents if the suction grip should fail.

The top of the stack is assumed in the foregoing to be kept in some way always at about the same level (minor departures therefrom being taken care of by the cups 13^a, which are yielding), say by utilizing a table which is automatically elevated as fast as the sheets are withdrawn, such being unnecessary of description herein since it forms no part of the present invention and is further well known in the art.

Having thus fully described my invention, what I claim is:

1. In a mechanism for removing sheets substantially horizontally and in succession from a sheet stack, the combination of a support having a substantially horizontal guideway, a reciprocatory carriage movable along the guideway, means in the carriage

to remove a sheet from the stack on each reciprocation of the carriage, and means to reciprocate the carriage including an oscillating lever fulcrumed on a substantially horizontal axis extending transversely of the path of travel of the carriage and having a direct sliding connection with the carriage consisting of a trunnion on the carriage and a longitudinal slot receiving the trunnion and formed in the lever.

2. In a mechanism for removing sheets substantially horizontally and in succession from the top of a sheet stack, the combination of a support, a substantially horizontally reciprocatory carriage movable on the support over the stack, means to grip the topmost sheet in the stack movable in the carriage downward to grip such sheet and then upwardly, and means to cause the downward and upward movement of the gripping means including a cam arranged on the support to be engaged by the gripping means at one point in the movement of the latter with said carriage.

3. In a mechanism for removing sheets substantially horizontally and in succession from the top of a sheet stack, the combination of a support, a reciprocatory system movable on the support over the stack, means to grip the topmost sheet in the stack movable in said system downward to grip such sheet and then upwardly, and means to cause the downward and upward movement of the gripping means including a lever structure fulcrumed in the support and adapted to be moved on its fulcrum by said system when the latter moves in one direction and thereupon to engage and move the gripping means in one of the up-and-down directions.

4. In a mechanism for removing sheets substantially horizontally and in succession from the top of a sheet stack, the combination of a support, a substantially horizontally reciprocatory carriage movable on the support over the stack, means to grip the topmost sheet in the stack movable in the carriage downward to grip such sheet and then upwardly and normally held upward, and means to cause the downward movement of the gripping means including a cam arranged on the support to be engaged by the gripping means at one point in the movement of the latter with said carriage.

5. In a mechanism for removing sheets substantially horizontally and in succession from the top of a sheet stack, the combination of a support, a reciprocatory system movable on the support over the stack, means to grip the topmost sheet in the stack movable in said system downward to grip such sheet and then upwardly and normally held upward, and means to cause the downward movement of the gripping means including a lever structure fulcrumed in the

support and adapted to be moved on its fulcrum by said system when the latter moves in one direction and thereupon to engage and move the gripping means downward.

5. In a mechanism for removing sheets substantially horizontally and in succession from the top of a sheet stack, the combination of a support, a carriage movable in the support to a position over the stack, means movable downward in the carriage to grip the topmost sheet, means to move said carriage to said position movable to a given limit and adapted to clear the carriage before such limit is reached, and means, actuated by the last-named means after clearing the carriage and before such limit is reached, to depress the gripping means.

6. In a mechanism for removing sheets substantially horizontally and in succession from the top of a sheet stack, the combination of a support, a carriage movable in the support to a position over the stack, means movable downward in the carriage

to grip the topmost sheet, means to check 25 the carriage when it reaches said position, and means movable in a given direction first to move the carriage to said position and then depress the gripping means.

8. In a mechanism for removing sheets substantially horizontally and in succession from the top of a sheet stack, the combination of a support, a carriage movable in the support substantially horizontally in a given direction from a position over the stack, 30 sheet-gripping means in the carriage movable upward in the carriage to lift the topmost sheet in the stack, said carriage having a depending portion relatively rearward of such sheet, and a detent normally projecting 35 from said portion in said direction and in overhanging relation to the rear edge of the stack and pivotally movable upward and adapted to be passed by said sheet on lifting thereof by said means.

40
45 In testimony whereof I affix my signature.

GUSTAV BORGESON.
